US00D925764S

(12) **United States Design Patent** (10) **Patent No.:** **US D925,764 S**
Becker (45) **Date of Patent:** **** Jul. 20, 2021**

(54) **BASE FOR MEDICAL IMPLANT AND/OR INSTRUMENT CASE**

(71) Applicant: **DePuy Synthes Products, Inc.**, Raynham, MA (US)

(72) Inventor: **Stephan Becker**, Lörrach (DE)

(73) Assignee: **DePuy Synthes Products, Inc.**, Raynham, MA (US)

(**) Term: **15 Years**

(21) Appl. No.: **29/735,862**

(22) Filed: **May 26, 2020**

(51) LOC (13) Cl. **24-01**

(52) U.S. Cl.

USPC **D24/217**

CLAIM

I claim the ornamental design for a base for a medical implant and/or instrument case, as shown and described.

DESCRIPTION

FIG. 1: is a perspective view of the base for a medical implant and/or instrument case from the top position;
FIG. 2: is a left side view and a right side view thereof;
FIG. 3: is a front view and a back view thereof;

(Continued)

FIG. 4: is a top view thereof; and,
FIG. 5: is a back view thereof.

1 Claim, 5 Drawing Sheets
